TACKER

Frank S. Boroughs, New York, N. Y., assignor to
 Arrow Fastener, Inc., Brooklyn, N. Y., a corporation of New York

Application August 6, 1948, Serial No. 42,760

26 Claims. (Cl. 1—49)

1

This invention relates to hand actuatable staple tackers. An object of this invention is to provide a device of the character described which shall have considerable power with relatively little movement of the handle, and which shall be comfortable to operate without tiring the hand.

Another object of this invention is to provide a device of the character described comprising a body, a staple magazine hinged at one end to the body and held in place on the body by a removable element and a front cover or nose likewise pivoted at one end to the body and held in place on the body by said element, whereby removal of said element will permit both the magazine and the nose to swing away from the body for cleaning or servicing the device.

Another object of this invention is to provide in a device of the character described, a staple pusher spring lock, means for retaining the staple pusher in place, said lock means being controlled by a handle, and the staple magazine being so arranged that when it is swung away from the body, it will automatically release the lock for the pusher.

Yet another object of this invention is to provide a device of the character described, a body, a handle pivoted to the body, a pawl pivoted to the handle, a trigger pivoted within the body and being connected to a spring pressed plunger, the arrangement being such that as the handle is pressed towards the body, the pawl on the handle will rotate the trigger to lift the plunger, and when the plunger is lifted a predetermined distance, the pawl will snap off the trigger to permit the plunger to be forced down for ejecting a staple, said trigger having means to prevent backing up of the plunger and being further provided with means to shove the pawl off the trigger should the pawl stick for any reason.

Yet another object of this invention is to provide in a device of the character described, a trigger having gear like mesh with the plunger so as to change the wearing point as the trigger rotates, whereby to prolong the useful operating life of the stapler.

Still a further object of this invention is to provide in a device of the character described, a trigger having a pair of trigger arms, a pawl having a pair of pawl arms engaging a pair of shoulders on the trigger, and the trigger arms having engagement with two pairs of detents on the plunger whereby to provide for more balanced operation and longer wear.

A still further object of this invention is to provide in a device of the character described, a

2

trigger having shoulders and a pawl pivoted to handle and having engagement with the trigger shoulders, the shape of the shoulders and the pawl being such as to release abruptly when the handle is depressed to a predetermined position.

A still further object of this invention is to provide a tacker of the character described comprising a casing having side walls recessed outwardly to give clearance for the detents on the plunger plug and also to give clearance for the trigger arms, which engage between the detents.

Still another object of this invention is to provide a strong, rugged, durable and compact hand staple tacker of the character described, which shall be relatively inexpensive to manufacture, easy to assemble and manipulate and which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims:

In the accompanying drawings in which are shown various illustrative embodiments of this invention.

20 Fig. 1 is a side elevational view of a device embodying the invention;

Fig. 2 is a cross sectional view taken on line 2—2 of Fig. 3;

25 Fig. 3 is a vertical, longitudinal cross sectional view, taken through the middle of device shown in Fig. 1.

Fig. 4 is a cross sectional view, taken on line 4—4 of Fig. 3;

30 Fig. 5 is a cross sectional view, taken on line 5—5 of Fig. 3;

Fig. 6 is a view similar to Fig. 3 but showing the handle depressed and in a position just before the pawl snaps off the shoulders on the trigger;

35 Fig. 7 is a cross sectional view, taken on line 1—1 of Fig. 6;

Fig. 8 is a partial vertical cross sectional view of the device and showing the staple pusher lock released and in retracted position;

40 Fig. 9 is a cross sectional view, taken on line 9—9 of Fig. 6.

Fig. 10 is a longitudinal vertical cross-sectional view of the stapler showing the front cover swung forwardly and the stapler magazine swung downwardly and with the staple pusher removed;

Fig. 11 is a cross-sectional view taken on line 11—11 of Fig. 3; and

Fig. 12 is a cross-sectional view taken on line 12—12 of Fig. 3.

Referring now in detail to the drawing, 10 designates a hand staple tacker embodying the invention. The same comprises generally a casing or body. The casing 11 comprises parallel side walls 20 from which extend inwardly top transversely curved walls 21, having meeting edges 21a in a vertical longitudinal plane bisecting the body. The wall 21 extending from each side wall is formed with a forwardly and upwardly curved extension 22 and a rearwardly and downwardly curved extension 23. The upper ends of walls 22 extend to the upper edges 24 of the side walls 20.

Said casing 11 is formed with a horizontal longitudinal through hand opening 25 (Fig. 6). The side walls 20 are interconnected by top and bottom walls 26 and 27 and end walls 28 and 29, forming a top, bottom and ends of the hand hold 25, said end walls 28 and 29 are semi-circular and interconnect the ends of walls 26 and 27. The walls 26, 27, 28 and 29 are of curved transverse cross-section. The side walls 20 have parallel lower edges 31 disposed in the same horizontal plane. Said casing is open at the bottom. It is also open at its front end and its upper end forwardly of wall 22. The rear, lower edges of walls 23 terminate substantially in the horizontal plane of the axes for the curved end walls 28 and 29 as indicated at 32, and hence the casing 11 is also open at its rear end, below said edge 32.

The side walls 20 are formed at their front ends with vertical forward edges 33 (Fig. 1) extending upwardly from the forward ends of the lower edges 31. The edges 33 extend up to a level somewhat below the level of a horizontal plane passing through the axes for the curved end walls 28 and 29. Extending from the upper ends of edges 33 a short distance rearwardly therefrom, are horizontal edges 34. The said side walls 20 are formed with outwardly recessed flat parallel U-shaped portions 35 above and rearwardly of the edges 34. Said portions 35 have forward vertical edges 36 extending upwardly from the rear ends of edges 34. Said portions 35 have parallel upper and lower ends 37 and 38, respectively, and a rear curved portion 39 interconnecting said portions 37 and 38. The portions 37, 38, and 39 interconnect the outwardly recessed areas or portions 35 with the main portions of wall 20. Extending forwardly from the upper ends of the vertical edges 36 of said portions 35, are edges 40, from the front ends of which extend upwardly vertical edges 41 merging with the top horizontal edges 24 by means of curved edges 42.

Said side walls 20 are furthermore formed adjacent the front edges 33 and above the lower edges 23 with aligned horizontal slots 45 disposed at a somewhat higher level than the inwardly grooved portions 44. Said side walls 20 are furthermore formed, just above the portions 37, thereof and adjacent the edges 41 thereof with aligned horizontal slots 46, for the purpose hereinafter appearing. The slots 46 are in vertical alignment with the slots 45.

Said side walls 20 are furthermore formed, somewhat rearwardly of the walls 27, with aligned punched openings 48 (Fig. 1), for the purpose hereinafter appearing. Said side walls 20 are also formed just below the edge 32 with notches 49 (Fig. 8), for the purpose hereinafter appearing. Said side walls 20 are furthermore

formed somewhat above the slots 46 with aligned round openings 50 (Fig. 6), for the purpose hereinafter appearing.

The portions 35 of walls 20 are furthermore formed with aligned openings 51 centered with respect to the curved portions 39. Said side walls are furthermore formed, somewhat above and rearwardly spaced with respect to the slots 45, with aligned through openings 52 (Fig. 6), for the purpose hereinafter appearing. Said side walls are also formed, above the rear end of portions 35, with outwardly pressed portions 54 having horizontal upper edges 55. The upper edges 55 are located somewhat below the centers 15 of the openings 50.

Below the notches 49 (Fig. 8), the rear ends of said walls 20 have edges 56 which extend upwardly from the rear ends of the lower edges 31. The edges 56 are somewhat inclined forwardly and upwardly at their upper ends as at 56a.

Mounted on and between the said walls 20 is a lower spacer 60 (Figs. 5 and 9). Said spacer 60 is horizontal and comprises a plate having at its opposite edges, extensions 61 terminating short of the front and rear edges of the spacer and projecting into the slots 45, thereby forming shoulders contacting the inner surfaces of walls 20 at opposite sides of said slots. At the front edge of spacer 60 is a longitudinal groove 62, for 30 the purpose hereinafter appearing. Said spacer plate 60 is formed with a central opening 63.

Mounted on and between said side walls 20 is an upper spacer 65 (Figs. 2 and 5). Said upper spacer 65 is horizontal and is provided at the sides hereof with projections 66 extending into slots 46 thereby forming shoulders at the ends of said slots engaging the inner surfaces of the walls 20. Said upper spacer 65 is formed with a central opening 67 and with a downward projecting annular flange 68 (Fig. 9) surrounding said opening.

Mounted on the front of the casing 11 is a front cover 70 (Fig. 10). Said front cover 70 comprises a front wall 71, from which there extend side walls 72. The front wall 71 is formed with a vertical forwardly recessed portion 73 spaced from the side walls 72 and spaced from the lower edge 74 of wall 71. The side walls 72 have lower end edges 75 flush with the lower end edges 31 of the side walls 20. Extending upwardly from the rear ends of the edges 75 are vertical edges 76 in alignment with the axes of the openings 52. Extending from the edges 76 are semi-circular edges 77 concentric with the axes of the openings 52. Extending forwardly from the upper ends of the semi-circular edges 77 are horizontal edges 78 terminating at the rear ends of the edges 34 of the side walls 20. Extending upwardly from the forward ends of edges 78 are vertical edges 79 terminating at the forward ends of portions 37 of the side walls 20. Extending rearwardly from the upper ends of the edges 79 are horizontal edge portions 80 from which extend upwardly and rearwardly curved edge portions 81. The edge 81 makes substantially three-quarters of a circle terminating at the front wall 72. There are thereby formed ears 82 at the upper ends of the said walls 72. The upper end of the front wall 71 is inclined upwardly and rearwardly as at 83 at its upper end, extending to a point somewhat above the axes of the ears 82. Said ears 82 are formed with through openings 82a registering with the openings 50 in the side walls 20. The side walls 72 of 75 the front cover are also formed with openings

registering with the openings 52 in the side walls 20.

Extending through openings 52 in the side walls 20 and the openings in the side wall 72 registering therewith, is a removable screw 85 having a head at one end and a reduced threaded portion at the opposite end receiving a nut 86. The screw 85 may be removed to permit the front cover to be swung upwardly and forwardly as will appear hereinafter. Extending through the openings 50 in the side wall 20 and the openings 82a in the ears 82 registering therewith, is a screw 87 having a head at one end and having reduced threaded portion at the opposite end receiving a nut 88.

It will now be understood that the front cover 70 is entirely removable and that also when the screw 85 is removed, the front cover can swing forwardly and upwardly about the screw 87 to permit servicing of the tacker.

Mounted on top of the lower spacer 60 (Fig. 9) is a soft compressible gasket or shock absorber 89 in the form of a disc made of rubber or rubber-like material, and the latter may be attached to the spacer 66 by means of a rivet 89a passing through the hole or central opening 63.

Between the lower ends of the said walls 20 of the casing is a staple magazine 90 (Fig. 10). Said magazine 90 comprises generally of a magazine frame 91 and a magazine rail 92 (Fig. 7). The frame 91 comprises a bottom wall 93 from which extends upwardly side walls 94 fitting within the side walls 20 of the casing. The bottom wall 93 terminates as at 93a in an edge short of the forward edges of the side walls 94. Extending inwardly from the upper ends of said side walls 94 are horizontally aligned flanges 95 projecting toward each other. Said flanges 95 terminate somewhat rearwardly of the front ends of the side walls 94, the latter being flush with the front end edges 33 of the side walls 20 of the casing, and forming with the front wall 71 of the front cover a slot 96 (Fig. 6) registering with the slot or groove 62 in the lower spacer 60 to receive a plunger blade 97 to be described in detail hereinafter. Extending upwardly from the inner ends of the flanges 95 at points spaced rearwardly of the forward ends of said flanges are upwardly extending parallel vertical walls 98 formed at their upper ends with outwardly extending horizontal flanges 99 (Fig. 7) from the outer ends of which extend upwardly vertical walls 100. The upper edges of the walls 100 are substantially at the level of portions 38 of the side walls 20. Extending inwardly from the forward ends of walls 100 are vertical flanges 101 (Fig. 6), which project toward each other and are located in a plane perpendicular to the side walls 20 and spaced rearwardly from the front walls of the front cover 70.

The walls 100 are formed with aligned openings registering with the openings 52 and through which the screw 85 passes. It will be noted that the forward ends of the side walls 94 of the magazine frame extend downwardly to the level of the undersurface of the bottom wall 93 forwardly of the forward edge 93a of said bottom wall, said side walls being notched at their lower edges just forwardly of said edge 93a.

Extending upwardly from the rear ends of the flanges 95 (Figs. 10 and 11) are vertical walls 102 from which extend outwardly horizontal shoulders 103 and extending from the outer ends of the shoulders 103 are upwardly extending ears 104 formed with aligned openings registering

with the openings 48 in the side walls 20. Extending through said openings 48 and through the openings in the ears 104 registering therewith is a horizontal pivot 105. It will now be understood that when the screw 85 is removed, not only can the front cover be swung forwardly and upwardly, but the staple magazine 90 may be swung downwardly and rearwardly, to permit servicing of the tacker.

10 The magazine rail 92 (Fig. 7) comprises a horizontal top wall 106 from which extend downwardly side walls 107. The walls 106 are spaced below the flanges 95, and the walls 107 are spaced inwardly of the side walls 94, providing space for the staples 108 which slide on the rail 92 and between said rail and the frame 91. Punched from the top wall 106 are downwardly pressed tongues 109 (Fig. 6) welded to the bottom wall 93 as at 110. The forward end of the top wall 106 is flush with the forward ends of the top flanges 95 so as to permit the plunger blade 97 to press the foremost staple 108 downwardly.

Mounted on the rail 92 is a staple pusher 112 of usual construction and including a member 113 slideable on said rail and having upwardly extending apertured ears 114 through which passes a pusher rod 115. The forward end of rod 115 is upset or enlarged in the usual manner so that the pusher will not come off said forward end. Fixed to the rear end of the rod 115 is a member 116 having a rear wall 117 disposed between the rear ends of the side walls 20. The wall 117 is flush with the rear edges 56. The rear end of the rod 115 is riveted thereto.

35 Extending from the sides of rear wall 117 are side walls 118 which fit between the side walls 20 and include upwardly extending apertured ears 119 carrying a transverse pivot pin 120. Pivoted to the pivot pin 120 is a pusher lock 121. Said pusher lock 121 comprises a rear wall 122 located between the upper end of wall 117 and the lower edge 32 of casing wall 23.

Extending from the sides of wall 122 are parallel wings 123 which fit into the notches 49. Extending from the sides of rear wall 122 are parallel walls 124 formed with openings through which pivot pin 120 passes. At the forward ends of the side walls 124 are hooks 125 adapted to snap into engagement with pivot 105 when the member 116 is pushed forwardly to locking position. On the bar 115 is a coil compression spring 126 contacting at its rear end an extension 127 at the lower end of rear wall 122. The forward end of the spring 126 contacts the pusher 113. The extension 127 straddles the rod 115 and is notched for such purpose. The spring 126 thus has two functions: it serves to push the pusher member 113 forwardly for advancing the staple strip; and it also serves to rotate the lock member 121 in a counterclockwise direction to engage hooks 125 with the pivot pin 105 for locking the pusher in place.

In order to remove the pusher, the wings 123 are engaged by the fingers of the operator and member 121 is rotated in a clockwise direction thereby releasing the hooks 125 from the pivot pin 105 and permitting the entire pusher assembly to be slidably moved rearwardly so that a new staple strip may be slipped onto the rail 92.

It will now be further understood that should the screw 85 be removed and the staple magazine swung downwardly and rearwardly, the rear end of the staple magazine will move upwardly. This upward movement causes wings 123 to slide upwardly in the lateral notches 49, at the same

time urging pusher lock 121 in a clockwise direction about its pivot pin 120 thus raising hooks 125 from locking engagement with the staple magazine pivot pin 105. Upon release of pusher lock 121, the entire assembly, comprising members 116 and 121, is urged outwardly to the right by the action of the pusher compression spring 126, thus clearing the way for the continued further upward movement of the rear end of the staple magazine frame 91, as the magazine completes its downward and rearward swinging movement about its pivot pin 105.

Slidably mounted within the casing 11 and between the side walls thereof, adjacent the front cover 70, is a plunger 130. The plunger 130 comprises a frame 131 which may be made of a single piece of metal. Said frame 131 comprises a bottom wall 132 which may be convex upwardly. Extending from the bottom wall 132 is a vertical front wall 133, a vertical rear wall 134 parallel to the front wall, and vertical side walls 135 parallel to one another and forming a chamber to receive the lower end of a coil compression spring 136 interposed between the bottom wall 132 and the upper stop on spacer member 46. The annular flange 68 of the upper spacer centers the upper end of the spring 136. The coil compression spring 136 tends to depress the plunger frame 131. The plunger blade or driver 97 is riveted to the front wall 133 as at 137 and projects downwardly therefrom contacting the inner surface of the front wall 71 and passing through groove 96 and groove 62 in the lower spacer, for driving the foremost staple in the staple strip. The forwardly recessed portion 73 of the front cover 71 provides the space necessary for the head of the rivet 137. As the plunger descends, the rear wall 134 will be engaged by the vertical flanges 101 of walls 100 of the staple magazine which serve as a guide for the plunger. As will be seen hereinafter, the plunger descends under the impact of a released previously compressed spring 136, and the lower wall 132 of the plunger frame will contact the shock absorber 89 which serves to absorb the shock of the blow.

The front wall 133 of plunger 130 (Figs. 3 and 6) may be formed with a pair of forwardly pressed prongs 140 punched from said front wall, to engage the front wall 71 of the cover for guiding the plunger as it moves up and down.

The rear wall 134 may be formed with a through opening 144 aligned with a rivet opening in the front wall 133 to facilitate application of the rivet 137 which rivets the plunger blade or driver 97 to said front wall.

It will be noted that the front wall 133 extends above the upper ends of the side and rear walls 135 and 134 and the extended portion of said front wall 133 is formed with a boss 145 contacting the inner surface of the front wall 71.

The side walls 135 of the plunger frame 131 are each formed with a pair of symmetrical outwardly pressed or punched detents or lugs 150 and 151 having inner inclined edges. The inner inclined edge of the upper detent 150 is inclined upwardly and rearwardly to an angle of about 15° to the horizontal, whereas the inner edge of the lower detent 151 is inclined downwardly and rearwardly to an angle of about 15° to the horizontal. The purpose of these detents or lugs will be described hereinafter.

Extending through the openings 51 in the portions 35 of the side walls 29 is a horizontal transverse pivot 153. Pivoted thereto is a trigger 154. Said trigger 154 comprises a bottom web or wall

155. Extending forwardly and upwardly from the forward end of web 155 is a curved tongue 156 adapted to contact the rear surface of rear wall 134. Extending upwardly from the rear end 5 of web 155 is a straight wall or tongue 157 disposed at right angles to the wall 155 for the purpose hereinafter appearing. Extending upwardly from the sides of the web 155 are parallel side walls or arms 158 having aligned openings registering with the openings 51 and through which the pivot 153 passes. The curved tongue 156 is concentric with the axis of the pivot 153 so that as the trigger 154 is rotated, the curved tongue 156 will remain in contact with wall 134 of the plunger. The arms 158 straddle the plunger frame and contact the outer surfaces of the side walls 135. At the forward ends of said arms 158 10 are heads 159 each shaped like a gear tooth and engaging between the inner edges of the detents or lugs 150, 151. Thus as the trigger 154 is rotated in a clockwise direction in the manner hereinafter appearing, the heads 159 engaging the detents 150 will raise the plunger. At a predetermined point in the lifting movement or operation of the plunger, the trigger is released, in a manner to be described hereinafter, and the compressed spring 136 will cause the plunger to descend with force, to drive a staple 108 for a tacking operation. At the rear ends of arms 158 15 and projecting beyond the wall or tongue 157 are curved lugs or shoulders 160, for the purpose hereinafter appearing.

On the screw 87 is a spacer bushing 87a. Pivoted on screw 87 is a handle 161. Said handle 35 comprises a top wall 162 the rear end of which is curved downwardly as at 163. At the forward end of the top wall 162 is a downwardly and forwardly inclined wall 164 having a front edge 165, adapted to contact the upper edge 166 of the upper end portion 83 of the front wall 71 of the cover when the handle is not pressed towards the casing 11. Extending from the top wall portions 162, 163 are parallel side walls or flanges 166. The handle is open at the bottom and at its forward end 165. At the forward end of the handle 40 are side wall portions 167 pressed outwardly and straddling the ears 82 of the front cover. At the forward ends of the side walls 167 are substantially semi-circular portions 168 formed with central openings registering with the openings 50 and with the openings 82a in the ears 82 and through which the screw 87 passes.

The bushing 87a (Fig. 9) passes through the openings 50 in the side walls 29 and serves as a spacer for the ears 82. The ends of the bushing 55 contact the inner surfaces of said ears 82 of the front cover 70. The side walls 166 and side wall portions 167 have lower edges 170, adapted to contact the upper edges 55 of the lugs 54 of the 60 side walls 29, when the handle is depressed, to limit swinging movement of the handle in clockwise direction, that is, from the full line to the dot-dash line position of Fig. 1. When the edges 170 contact the lugs 54 said edges 170 will be substantially in a horizontal position. As the handle is depressed, edge 165 will move away from edge 166 as shown in Fig. 6 of the drawings.

Disposed about the bushing 87a is a handle return torsion spring 172. One end 173 of the spring 70 contacts the underside of the top wall portion 164 of the handle, whereas another end 174 of the spring contacts the rear edge of the upper spacer 65. The torsion spring 172 tends to lift the handle and said spring is tensioned when the handle is depressed.

Fixed to the underside of wall 162 of the handle is a pawl bracket 176. Said pawl bracket has top aligned top wall portions 177 and 178 contacting the underside of said wall 162. Interconnecting said wall portions 177 and 178 are side wall portions 179 disposed within and spaced from the side walls 169. The walls 179 are formed with aligned openings 180 receiving a transverse horizontal pivot 181 spaced below the wall 162. Wall 177 may be riveted to the wall 162 by means of a rivet 181. The said walls 179 may be formed with slots 182 to straddle the walls 22 of the casing 11 when the handle is depressed. Pivot to the rivet 181 is the pawl member 185. Said pawl member 185 comprises a top wall 186 from which extend downwardly parallel pawls 187. Said pawls 187 are formed, somewhat below the top wall 186, with openings registering with the openings 180 and through which the pivot pin 181 passes. The pawl member is thus pivoted on the pivot pin 181 and may move relative to the handle 161. The top wall 186 of the pawl member is located between the top wall portions 177 and 178 of the pawl bracket 176. On the pivot pin 181 is a coil torsion spring 188 which tends to rotate the pawl 185 in a clockwise direction relative to the handle, looking at Fig. 3 of the drawings. The torsion spring 188 has one end 190 which contacts the underside of the top wall 186 of said pawl 185. The other end 191 of the torsion spring contacts the underside of the top wall 177 of the pawl bracket. The lower ends of the pawls 187 engage the curved shoulder extensions or lugs 168 of the trigger.

When the handle is depressed from the position shown in Fig. 3 to the position shown in Fig. 6, the trigger is rotated in a clockwise direction raising the plunger and loading the spring 136. At the same time the pawl member 185 will be turned in a counterclockwise direction relative to the handle. When the plunger is fully raised to a predetermined position, the lower ends of the pawl will snap off the shoulders or lugs 168, permitting the loaded spring 136 to depress the plunger and drive a staple.

When the handle is released and swings upwardly in a counterclockwise direction relative to the casing, the pawl member 185 under the influence of the torsion spring 188 will be moved back to normal position so that the pawls 187 again engage shoulders 168. Should the pawl fail to snap off the lugs 168 when the plunger is fully raised to a predetermined position, the upper end of wall or tongue 157 will push the pawls off said lugs at the proper point in the rotation of the trigger, thus serving as a safety factor to insure release of the plunger at the proper point.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to protect by Letters Patent of the United States:

1. In a staple tacker, a body, a handle pivoted to the body, a staple magazine within the body, a plunger slidably mounted within the body, a

driver blade fixed to the plunger slidably therewith and adapted to drive staples from the staple magazine when the plunger descends, a trigger pivoted meditately the ends thereof to the body on a pivot disposed below the handle, means on the front end of the trigger engaging the plunger for lifting the latter, spring means to press the plunger downwardly, a pawl movable with the handle disposed rearwardly of the pivotal connection between the handle and the body and projecting downwardly therefrom, the lower end of the pawl releasably engaging the rear end of the trigger, whereby when the handle is pressed downwardly toward the body the pawl will rotate the trigger about its pivotal axis to raise the plunger, said trigger being swingable to an angle where the pawl slides rearwardly off the rear end of the trigger and disengages itself from the trigger to release the latter during said downward movement of the handle toward the body, and means on the trigger to push the pawl off the trigger should the pawl fail to slide off the trigger.

2. In a staple tacker, a body, a handle pivoted to the body, a staple magazine within the bottom of the body, a plunger slidably mounted within the front end of the body, a driver blade fixed to the plunger, slidably therewith and adapted to drive staples from the staple magazine when the plunger descends, a trigger pivoted meditately the ends thereof to the body on a pivot disposed below the handle, means on the front end of the trigger for raising the plunger, spring means to press the plunger downwardly, a pawl movable with the handle and projecting downwardly therefrom, the lower end of the pawl releasably engaging the rear end of the trigger for pivotally moving the trigger about its axis to raise the plunger when the handle is rotated toward the body, and means on the trigger to push the pawl off the rear end of the trigger when the trigger reaches a predetermined angle as it is swung about its axis.

3. A hand staple tacker comprising a body, a handle pivoted to the body, a staple magazine within said body, a plunger slidably mounted within said body, a driver blade fixed to the plunger and adapted to drive staples from the staple magazine when the plunger descends, a trigger pivoted to the body and having means for raising the plunger, spring means to cause the plunger to descend when the trigger is released, means including a pawl carried by the handle and releasably engaging the trigger for pivotally moving the trigger to raise the plunger when the handle is rotated about its pivot toward said body, said trigger having a curved projection engageable by the pawl, said pawl being adapted to slide off said projection when said trigger reaches a predetermined angular position to release said trigger, spring means for urging the pawl into engagement with said trigger, and means on the trigger to move said pawl off said projection when said trigger is rotated to a predetermined angular position, said plunger comprising a member having forwardly converging detents, and said trigger having a head engageable between said detents.

4. A hand staple tacker comprising a body, a handle pivoted to the body, a staple magazine within said body, a plunger slidably mounted within said body, a driver blade fixed to the plunger and adapted to drive staples from the staple magazine when the plunger descends, a trigger pivoted to the body and having means for

11

raising the plunger, spring means to cause the plunger to descend when the trigger is released, means including a pawl carried by the handle and releasably engaging the trigger for pivotally moving the trigger to raise the plunger when the handle is rotated about its pivot toward said body, said trigger having a curved projection engageable by the pawl, said projection being so curved that said pawl will slide off said projection when said trigger reaches a predetermined angular position to release said trigger, spring means for urging the pawl into engagement with said trigger, means on the trigger to move said pawl off said projection when said trigger is rotated to a predetermined angular position, said plunger comprising a member having detents, said trigger having a head engageable between said detents, said trigger being inclined downwardly and toward the plunger when the handle is in normal position before it is pressed towards said body, and said trigger being inclined upwardly and toward the plunger when the handle is pressed toward the body to the point where the pawl slides off the projection on the trigger.

5. A hand stapler comprising a body having side walls, and being open at the bottom and at its front end, a front cover pivoted adjacent its upper end to the body and covering the front open end of the body, a staple magazine within the lower open end of the body and extending longitudinally of the lower end of the body, means to pivot the staple magazine adjacent its rear end to the body, and removable means to interpivot the front cover below its upper pivoted end, and the staple magazine forwardly of its rear pivoted end, to the body, whereby upon removal of said interpivot means, said front cover may swing forwardly and upwardly about its upper pivot, and said staple magazine may swing downwardly and rearwardly about its rear pivot.

6. A hand stapler comprising a body having side walls, and being open at the bottom and at its front end, a front cover pivoted adjacent its upper end to the body and covering the front open end of the body, a staple magazine within the lower open end of the body and extending longitudinally of the lower end of the body, means to pivot the staple magazine adjacent its rear end to the body, and removable means to interpivot the front cover below its upper pivoted end, and the staple magazine forwardly of its rear pivoted end, to the body, whereby upon removal of said interpivot means, said front cover may swing forwardly and upwardly about its upper pivot, and said staple magazine may swing downwardly and rearwardly about its rear pivot, a staple pusher for said staple magazine including a rod, a member adapted to press a staple strip on the staple magazine toward the discharge end of the magazine, a spring on said rod for urging the staple strip press means toward said discharge end, a member fixed to the rear end of said rod, a hook pivoted to said member, said spring engaging said hook to pivotally move the hook in one direction and urge said hook into engagement with the means for pivoting the rear end of said staple magazine to said body, and a handle on said hook to pivotally move the hook in an opposite direction and disengage the hook from said means which pivots the rear end of said staple magazine to said body.

7. A hand staple tacker comprising a hollow body having side walls, said body being open at its lower end and at its forward end, a lower stop member interconnecting said side walls adjacent

the forward end of the body, a top stop member interconnecting said side walls and spaced above the bottom stop, a plunger slidably mounted within the body and between said bottom stop and top stop, a spring interposed between the plunger and the top stop, a driver blade attached to said plunger and projecting downwardly therefrom, a front cover at the front of said body, means to raise the plunger to compress the spring and to release the raised plunger so that the compressed spring will cause the plunger to descend, and a shock absorber on said bottom stop and adapted to be contacted by the plunger when the plunger descends, said plunger comprising a bottom wall, front and rear walls extending upwardly from said bottom wall, and side walls extending upwardly from said bottom wall, a trigger pivoted to said body and having arms straddling the sides of said plunger, the side walls on said plunger each being formed with a pair of outwardly pressed projections, said arms having heads received between said projections.

8. A hand staple tacker comprising a hollow body having side walls, said body being open at its lower end and at its forward end, a lower stop member interconnecting said side walls adjacent the forward end of the body, a top stop member interconnecting said side walls and spaced above the bottom stop, a plunger slidably mounted within the body and between said bottom stop and top stop, a spring interposed between the plunger and the top stop, a driver blade attached to said plunger and projecting downwardly therefrom, a front cover at the front of said body, means to raise the plunger to compress the spring and to release the raised plunger so that the compressed spring will cause the plunger to descend and a shock absorber on said bottom stop and adapted to be contacted by the plunger when the plunger descends, said plunger comprising a bottom wall, front and rear walls extending upwardly from said bottom wall, and side walls extending upwardly from said bottom wall, a trigger pivoted to said body and having arms straddling the sides of said plunger, the side walls on said plunger each being formed with a pair of outwardly pressed projections, said arms having heads received between said projections, said projections on each side wall converging forwardly and said heads having edges converging forwardly.

9. A hand staple tacker comprising a hollow body having side walls, said body being open at its lower end and at its forward end, a lower stop member interconnecting said side walls adjacent the forward end of the body, a top stop member interconnecting said side walls and spaced above the bottom stop, a plunger slidably mounted within the body and between said bottom stop and top stop, a spring interposed between the plunger and the top stop, a driver blade attached to said plunger and projecting downwardly therefrom, a front cover at the front of said body, means to raise the plunger to compress the spring and to release the raised plunger so that the compressed spring will cause the plunger to descend, a shock absorber on said bottom stop and adapted to be contacted by the plunger when the plunger descends, said plunger comprising a bottom wall, front and rear walls extending upwardly from said bottom wall, and side walls extending upwardly from said bottom wall, a trigger pivoted to said body and having arms straddling the sides of said plunger, the side walls on said plunger each being formed with a pair

of outwardly pressed projections, said arms having heads received between said projections, said projections on each side wall converging forwardly and said heads having edges converging forwardly, said trigger having a forwardly and upwardly curved wall adapted to contact the rear of said back wall of said plunger, as said trigger is rotated.

10. A staple tacker comprising a body having a pair of side walls, a front wall at the front ends of said side walls, a pivot pin interconnecting said walls, a plunger slidably mounted for up and down movement between said side walls forwardly of said pivot pin and adjacent the front wall, said plunger comprising a bottom wall, parallel front and rear walls extending upwardly from the bottom wall, and parallel side walls extending upwardly from said bottom wall, said side walls of said plunger each having a pair of outwardly pressed forwardly converging projections, a plunger blade fixed to the front wall of the plunger and projecting downwardly therefrom, a trigger pivoted to said pivot pin, and comprising a bottom wall and a pair of parallel side arms extending upwardly from the bottom wall, heads at the forward ends of said side arms received between the pairs of projections on said side walls, a handle pivoted to said body, pawl means movable with the handle and comprising a pair of parallel downwardly projecting pawls, said side arms having projecting curved lugs engaged by the lower ends of said pawls.

11. A staple tacker comprising a body having a pair of side walls, a front wall at the front ends of said side walls, a pivot pin interconnecting said walls, a plunger slidably mounted for up and down movement between said side walls forwardly of said pivot pin and adjacent the front wall, said plunger comprising a bottom wall, parallel front and rear walls extending upwardly from the bottom wall, and parallel side walls extending upwardly from said bottom wall, said side walls of said plunger each having a pair of outwardly pressed forwardly converging projections, a plunger blade fixed to the front wall of the plunger and projecting downwardly therefrom, a trigger pivoted to said pivot pin, and comprising a bottom wall and a pair of parallel side arms extending upwardly from the bottom wall, heads at the forward ends of said side arms received between the pairs of projections on said side walls, a handle pivoted to said body, pawl means movable with the handle and comprising a pair of parallel downwardly projecting pawls, said side arms having projecting curved lugs engaged by the lower ends of said pawls, a forwardly and upwardly extending curved wall extending from the bottom wall of said trigger, and adapted to contact said rear wall of said plunger as said plunger moves up and down.

12. A staple tacker comprising a body having a pair of side walls, a front wall at the front ends of said side walls, a pivot pin interconnecting said walls, a plunger slidably mounted for up and down movement between said side walls forwardly of said pivot pin and adjacent the front wall, said plunger comprising a bottom wall, parallel front and rear walls extending upwardly from the bottom wall, and parallel side walls extending upwardly from said bottom wall, said side walls of said plunger each having a pair of outwardly pressed forwardly converging projections, a plunger blade fixed to the front wall of the plunger and projecting downwardly therefrom, a trigger pivoted to said pivot pin, and comprising a bottom wall and a pair of parallel side arms extending upwardly from the bottom wall, heads at the forward ends of said arms received between the pairs of projections on said side walls, a

comprising a bottom wall and a pair of parallel side arms extending upwardly from the bottom wall, heads at the forward ends of said side arms received between the pairs of projections on said side walls, a handle pivoted to said body, pawl means movable with the handle and comprising a pair of parallel downwardly projecting pawls, said side arms having projecting curved lugs engaged by the lower ends of said pawls, a forwardly and upwardly extending curved wall extending from the bottom wall of said trigger, and adapted to contact said rear wall of said plunger as said plunger moves up and down, and a wall extending upwardly from the rear end of the bottom wall of said trigger and between the side wall thereof, and adapted to push the pawls off the extending lugs of the trigger at a predetermined angular position in the rotation of said trigger.

13. A staple tacker comprising a body having a pair of side walls, a front wall at the front ends of said side walls, a pivot pin interconnecting said walls, a plunger slidably mounted for up and down movement between said side walls forwardly of said pivot pin and adjacent the front wall, said plunger comprising a bottom wall, parallel front and rear walls extending upwardly from the bottom wall, and parallel side walls extending upwardly from said bottom wall, said side wall of said plunger each having a pair of outwardly pressed forwardly converging projections, a plunger blade fixed to the front wall of the plunger and projecting downwardly therefrom, a trigger pivoted to said pivot pin, and comprising a bottom wall and a pair of parallel side arms extending upwardly from the bottom wall, heads at the forward ends of said side arms received between the pairs of projections on said side walls, a handle pivoted to said body, pawl means movable with the handle and comprising a pair of parallel downwardly projecting pawls, said side arms having projecting curved lugs engaged by the lower ends of said pawls, a forwardly and upwardly extending curved wall extending from the bottom wall of said trigger, and adapted to contact said rear wall of said plunger as said plunger moves up and down, a wall extending upwardly from the rear end of the bottom wall of said trigger and between the side walls thereof, and adapted to push the pawls off the extending lugs of the trigger at a predetermined angular position in the rotation of said trigger, a staple magazine within the bottom of the body, including a fixed guide wall contacting the rear wall of said plunger to guide the same in its up and down movement.

14. A staple tacker comprising a body having a pair of side walls, a front wall at the front ends of said walls, a pivot pin interconnecting said walls, a plunger slidably mounted for up and down movement between said side walls forwardly of said pivot pin and adjacent the front wall, said plunger comprising a bottom wall, parallel front and rear walls extending upwardly from the bottom wall, and parallel side walls extending upwardly from said bottom wall, said side walls of said plunger each having a pair of outwardly pressed forwardly converging projections, a plunger blade fixed to the front walls of the plunger and projecting downwardly therefrom, a trigger pivoted to said pivot pin, and comprising a bottom wall and a pair of parallel side arms extending upwardly from the bottom wall, heads at the forward ends of said arms received between the pairs of projections on said side walls, a

handle pivoted to said body, pawl means movable with the handle and comprising a pair of parallel downwardly projecting pawls, said side arms having projecting curved lugs engaged by the lower ends of said pawls, a forwardly and upwardly extending curved wall extending from the bottom wall of said trigger, and adapted to contact said rear wall of said plunger as said plunger moves up and down, and a wall extending upwardly from the rear end of the bottom wall of said trigger and between the side walls thereof, and adapted to push the pawls off the extending lugs of the trigger at a predetermined angular position in the rotation of said trigger, a staple magazine within the bottom of the body, including a fixed guide wall contacting the rear wall of said plunger to guide the same in its up and down movement, a bottom stop between the side walls of the body and supported thereby and disposed below the plunger, a top stop mounted on and between the side walls of said body and above said plunger, and a spring, the lower end of which is received within said plunger and contacting the bottom end of said plunger and the upper end of said spring engaging the underside of said top stop.

15. A hand staple tacker comprising a hollow body open at its lower and front ends, and open at the top adjacent the forward end of the body, a handle pivoted at its forward end to the body on a pivot pin interconnecting the side walls of the body, a front cover member pivoted to the body about said pivot pin and adapted to cover the front of the body, removable means to connect the lower end of the front cover to said body whereby upon removal of said removable means, said front cover may be swung upwardly and forwardly about its upper pivot, a plunger slidably mounted for up and down movement within said body adjacent the front cover, trigger means to raise said plunger, pawl means movable with the handle and adapted to rotate said trigger means for raising said plunger, and a staple magazine at the bottom end of the body and closing said bottom end.

16. A hand staple tacker comprising a hollow body open at its lower and front ends, and open at the top adjacent the forward end of the body, a handle pivoted at its forward end to the body on a pivot pin interconnecting the side walls of the body, a front cover member pivoted to the body about said pivot pin and adapted to cover the front of the body, removable means to connect the lower end of the front cover to said body whereby upon removal of said removable means, said front cover may be swung upwardly and forwardly about its upper pivot, a plunger slidably mounted for up and down movement within said body adjacent the front cover, trigger means to raise said plunger, spring means to lower said plunger, pawl means movable with the handle and adapted to rotate said trigger means for raising said plunger, a staple magazine at the bottom end of the body and closing said bottom end, spring means on said pivot pin for swinging the handle away from the body, and spring means for rotating said pawl means into engagement with said trigger means.

17. A hand staple tacker comprising a hollow body open at its lower and front ends, and open at the top adjacent the forward end of the body, a handle pivoted at its forward end to the body on a pivot pin interconnecting the side walls of the body, a front cover member attached to the body

by said pivot pin and adapted to cover the front of the body, means to connect the lower end of the front cover to said body, a plunger slidably mounted for up and down movement within said body adjacent the front cover, trigger means to raise said plunger, spring means to lower said plunger, pawl means movable with the handle and adapted to rotate said trigger means for raising said plunger, a staple magazine at the bottom end of the body and closing said bottom end, spring means on said pivot pin for swinging the handle away from the body, spring means for rotating said pawl means into engagement with said trigger means, and means on the trigger to guide the plunger in its up and down movement.

18. A hand staple tacker comprising a body, a handle pivoted to the body, a staple magazine within said body, a plunger slidably mounted within said body, a driver blade fixed to the plunger and adapted to drive staples from the staple magazine when the plunger descends, a trigger pivoted to the body and having means for raising the plunger, spring means adapted to be compressed upon raising the plunger and adapted to cause the plunger to descend when the trigger is released, pawl means movable with the handle and releasably engaging the trigger for pivotally moving the trigger to raise the plunger when the handle is rotated about its pivot toward said body, and means on said trigger to disengage said pawl means from said trigger at a predetermined angular position of said trigger.

19. A hand staple tacker comprising a body, a handle pivoted to the body, a staple magazine within said body, a plunger slidably mounted within said body, a driver blade fixed to the plunger and adapted to drive staples from the staple magazine when the plunger descends, a trigger pivoted to the body and having means for raising the plunger, spring means adapted to be compressed upon raising the plunger and adapted to cause the plunger to descend when the trigger is released, pawl means movable with the handle and releasably engaging the trigger for pivotally moving the trigger to raise the plunger when the handle is rotated about its pivot toward said body, and means on said trigger to guide said plunger for up and down movement as said trigger rotates.

20. A hand staple tacker comprising a body, a handle pivoted to the body, a staple magazine within said body, a plunger slidably mounted within said body, a driver blade fixed to the plunger and adapted to drive staples from the staple magazine when the plunger descends, a trigger pivoted to the body and having means for raising the plunger, spring means adapted to be compressed upon raising the plunger and adapted to cause the plunger to descend when the trigger is released, and pawl means movable with the handle and releasably engaging the trigger for pivotally moving the trigger to raise the plunger when the handle is rotated about its pivot toward said body, said trigger having forwardly converging projections and said plunger having means at its forward end disposed between said projections for connecting the trigger to the plunger.

21. A hand staple tacker comprising a body, a staple magazine within said body, a plunger slidably within said body, a driver blade fixed to the plunger and adapted to drive staples through the staple magazine when the plunger descends, staple pushing mechanism on the magazine comprising a staple pusher, a rod extending longitudinally of the magazine and slidably engaging the pusher,

a member fixed to the rear end of the rod and carrying a pivot pin, a hook pivoted to the pivot pin, fixed means on the body engageable by said hook, and a spring on the rod interposed between the pusher and the hook for pressing the pusher forwardly against a staple strip on the magazine and to retain the hook in engagement with said fixed means.

22. A hand staple tacker comprising a body, a staple magazine within the body, means to drive staples from the magazine, a staple pusher mechanism on the magazine and comprising a pusher slidable within the magazine, a rod slidably engaging said pusher, a hook pivotally connected to the rod, fixed means on the body engageable by the hook, and a single spring means on said rod to press the pusher forwardly towards the discharge end of the magazine and to retain the hook in engagement with said fixed means on said body.

23. A stapling device comprising a body having an open bottom, a transverse pin fixed within said body above the open bottom and adjacent the rear end of the body, a staple magazine disposed within the body at the open bottom and being pivoted to said transverse pin and being swingable downwardly and rearwardly about said pin, detachable means for attaching the front end of the staple magazine to the body to locate the magazine at the bottom of the body, a staple guide fixed within said magazine, pusher mechanism comprising a pusher slidable on said staple guide, a pusher rod on which said pusher is slidably mounted and disposed longitudinally of the guide, a bracket fixed to the rear end of the pusher rod and having a rear downwardly extending wall and a pair of parallel upstanding ears carrying a transverse pivot pin, a hook member pivoted to the transverse pin on said bracket and having a hook portion engageable with the transverse pivot pin on said body.

24. A stapling device comprising a body having an open bottom, a transverse pin fixed within said body above the open bottom and adjacent the rear end of the body, a staple magazine disposed within the body at the open bottom and being pivoted to said transverse pin and being swingable downwardly and rearwardly about said pin, detachable means for attaching the front end of the staple magazine to the body to locate the magazine at the bottom of the body, a staple guide fixed within said magazine, pusher mechanism comprising a pusher slidable on said staple guide, a pusher rod on which said pusher is slidably mounted and disposed longitudinally of the guide, a bracket fixed to the rear end of the pusher rod and having a rear downwardly extending wall and a pair of parallel upstanding ears carrying a transverse pivot pin, a hook member pivoted to the transverse pin on said bracket and having a hook portion engageable with the transverse pivot pin on said body, said hook member having a rear wall provided with a downward extension contacting the inner side of the rear wall of said bracket, and a coil compression spring on said rod and interposed between said pusher and said downward extension.

25. A stapling device comprising a body having an open bottom, a transverse pin fixed within said body above the open bottom and adjacent the rear end of the body, a staple magazine disposed within the body at the open bottom and being pivoted to said transverse pin and being

swingable downwardly and rearwardly about said pin, detachable means for attaching the front end of the staple magazine to the body to locate the magazine at the bottom of the body, a staple

5 guide fixed within said magazine, pusher mechanism comprising a pusher slidable on said staple guide, a pusher rod on which said pusher is slidably mounted and disposed longitudinally of the guide, a bracket fixed to the rear end of the pusher rod and having a rear downwardly extending wall and a pair of parallel upstanding ears carrying a transverse pivot pin, a hook member pivoted to the transverse pin on said bracket and having a hook portion engageable with the transverse pivot pin on said body, said hook member having a rear wall provided with a downward extension contacting the inner side of the rear wall of said bracket, and a coil compression spring on said rod and interposed between said pusher and said downward extension, said magazine having a bottom wall formed with a rear edge disposed adjacent the rear wall of the bracket.

26. A stapling device comprising a body having an open bottom, a transverse pin fixed within said body above the open bottom and adjacent the rear end of the body, a staple magazine disposed within the body at the open bottom and being pivoted to said transverse pin and being swingable downwardly and rearwardly about said pin, detachable means for attaching the front end of the staple magazine to the body to locate the magazine at the bottom of the body, a staple guide fixed within said magazine, pusher mechanism comprising a pusher slidable on said staple guide, a pusher rod on which said pusher is slidably mounted and disposed longitudinally of the guide, a bracket fixed to the rear end of the pusher rod and having a rear downwardly extending wall and a pair of parallel upstanding ears carrying a transverse pivot pin, a hook member pivoted to the transverse pin on said bracket and having a hook portion engageable with the transverse pivot pin on said body, said hook member having a rear wall provided with a downward extension contacting the inner side of the rear wall of said bracket, and a coil compression spring on said rod and interposed between said pusher and said downward extension, the rear wall of the hook member having an upwardly extending wings, and said body having notches to receive said wings.
